The ornamental design for an electronic combination lock housing, as shown and described.

DESCRIPTION

FIG. 1 is a left elevated perspective view of our first embodiment of an electronic combination lock housing showing our new design;

FIG. 2 is a right depressed perspective view of a first and second embodiment thereof;

FIG. 3 is a front elevational view of the first and second embodiment thereof;

FIG. 4 is a left elevational perspective view of the second embodiment thereof; and,

FIG. 5 is a rear elevational view of both embodiments thereof.
